UNITED STATES PATENT OFFICE.

WILLIAM ERASTUS WILLIAMS, OF CHICAGO, ILLINOIS.

MELTING-FURNACE.

SPECIFICATION forming part of Letters Patent No. 792,642, dated June 20, 1905.

Application filed June 20, 1903. Serial No. 162,417.

To all whom it may concern:

Be it known that I, WILLIAM ERASTUS WILLIAMS, a citizen of the United States of America, and a resident of Chicago, county of Cook, 5 and State of Illinois, have invented certain new and useful Improvements in Melting-Furnaces, of which the following is a specification.

The object of my invention is to provide a furnace for melting, smelting, refining, puddling, or roasting metals or ores that will be 10 of the simplest form, most convenient and efficient, and one wherewith the fuel and blast are heated by the waste heat of the escaping gases.

Reference will be had to the accompanying drawings, in which—

Figure 1 is a side sectional elevation of the furnace. Fig. 2 is a plan sectional detail showing the pinion that revolves the furnace-body. Fig. 3 is a side elevation with the parts in a different position from that of Fig. 1. Fig. 4 is a section of one of the foundation-blocks on line 4 4 of Fig. 3. Fig. 5 is a plan of Fig. 3. Fig. 6 is a section on line 6 6 of Fig. 1. Fig. 7 is a section on line 7 7 of Fig. 1.

My furnace preferably uses gaseous liquid or powdered fuel; but some features of it may be used with any kind of fuel.

In the drawings, 2 designates the furnace-body, composed of a casing 3, lined with suitable refractory material 4, thereby forming the interior chamber 5, which I prefer to be 30 nearly spherical in shape with a conical frustum projection 6 at one point for the opening to the chamber, this being the only opening to the furnace-chamber when the same is in use. However, any suitably-shaped body or chamber may be used.

The casing 3 is made with a removable bottom section 7, which permits access to the interior of the chamber in lining it. The furnace-body 2 is mounted to revolve in a ring 8 and is retained therein by means of a circular gear-rack 9, fastened to the casing 3 and retained in ring 8 by ribs 56 and 10. The ring 8 is mounted on trunnions 11 and 12, supported in journals in posts 13 and 14. The trunnion 11 is hollow, and through it passes 45 a shaft 15, which carries a pinion 16, which

engages the teeth of rack 9. Upon shaft 15 there is mounted a worm-gear 17, engaged and driven by a worm 18, splined upon shaft 19, which is driven by a pulley 20, whereby power is applied to cause the furnace 2 to revolve within the ring 8. A clutch 21 is provided to engage the pulley 20 with shaft 19 where the furnace 2 is to remain at rest. Upon trunnion 11 there is a worm-gear 22, which is engaged by a worm 23, splined upon shaft 24, extending back and driven by a set of pulleys 25 26 27. Pulley 26 is loose at all times and runs upon a sleeve connected to pulley 25 and 27, which latter may be engaged as desired by clutch 28 to drive shaft 24. The belts which drive the pulleys are arranged to travel in different directions, so that by shifting the belts and engaging and disengaging the clutches the shaft 24 may be made to travel in either direction, thereby 70 causing the ring 8 and the furnace 2 to revolve about the axis of the trunnions as desired.

A hand-wheel 29, mounted on a shaft 30, carrying a bevel-gear 31, which engages a 75 bevel-gear 32, connected to worm 23, permits the furnace to be revolved about the trunnions by hand when desired. The stands or posts 13 and 14 are mounted to slide upon the base or foundation blocks 33 and are secured 80 thereto by bolts 34, passing through slots 35 in base-blocks and through gib-bars 36, located in cavities 37 of base-blocks. Extending across the base-blocks there is a rocker-shaft 38, provided with handles 39 and adjustable links 40, which latter are connected to the stands 13 and 14, whereby the stands, and hence the furnace-body, may be moved along the base-blocks when the gib-bars 36 are not clamped tightly. Mounted in a fixed 90 position there is the flue-section 41, composed of an outer casing inclosing an inner flue 42. The outer flue terminates at the bottom in a large flange 43, adapted to fit over the projection 6 of the furnace-body 2, and the inner 95 flue 42 extends below the flange 43 and is provided with a deflecting enlargement 44. The material of these flues and casings may be such as is adapted for the purpose.

The annular space 57 around the flue 42 is 100

the duct for the air-blast supplied to the furnace, and it is connected to any suitable blast-engine or blower by the pipe 45, provided with a valve 46. The flue 42 is the chimney-flue for the escape of the gases from the furnace.

The liquid or gaseous fuel is supplied to the furnace by the pipe 47, provided with valve 48, and the pipe 47 is arranged to pass inside the flue 42, with a section 49, which is exposed to the heat of the escaping gases, and thereby heats the fuel on its entry to the furnace. The pipe 49 then passes out and is connected to a ring 50, connected to the jet-pipes 51, extending down in a direction to discharge into the furnace-chamber toward its lower outer portions and be commingled with the air-blast and burned as fast as the blast and fuel come together at the fuel-jets. The entering blast in the annular space 57 is heated by the heat of the escaping furnace-gases through the flue 42.

A vent-hole 52 out from flue 42 to the open air permits the attendant to notice the condition of the escaping furnace-gases, and this vent is closed as desired by the cover 53, held in place by the rocker-shaft 54, provided with the weighted lever 55, which keeps the vent normally closed. The flues for the escaping gases and the entering blast may be carried to any suitable position and arranged with heaters, whereby a larger radiation may be secured than is possible with the limited amount of space shown by the drawings. The arrangement of the flues after leaving the furnace may be such that the gases and blast may be passed through brickwork stoves, as is common in other furnace-work.

The object sought in my invention is to provide a means of connecting the air and blast to a furnace of the type shown that will permit such an arrangement.

The shape of the furnace and the arrangement of the blast and exhaust flues cause a rotary action of the flames that imparts greater heat to the furnace than is otherwise obtainable.

The operation of the furnace is as follows: The furnace-body is righted up from position of Fig. 3, so that the opening at 6 is in position to be accessible, and a small fire of wood or a few live coals are placed in the chamber 5. Then the furnace is revolved, either by hand or power, about the trunnion until the projection 6 is in position to be engaged by flange 43 of flue-casing 41. Then the rocker-shaft 38 is rotated, bringing the projection 6 into snug embrace of flange 43, and this position is maintained by the rocker-shaft being locked by having the pivots of the links pass the dead-centers of their thrust or by locking the rocker-shaft or by clamping the stands by means of the bolts to the base-blocks. The blast and fuel are now turned on, and the fuel is ignited by the fire or coals above mentioned.

The furnace-body 2 is made to revolve in the ring 8 by means of the pulley 20 and the mechanism of shafts and gearing before described. After the furnace is sufficiently heated up, the blast and fuel are shut off and the furnace-body 2 is disengaged from flange 43 and turned over in position to receive charge. When charged, the body 2 is again connected to flange 43 and the flues, the blast and fuel are turned on, and the body is set in motion, revolving within the ring 8, as before described. Thus the contents of the furnace are constantly exposed to the freshly-heated portion of the lining that comes underneath it as the furnace revolves, and the melted metal keeps flowing down to the bottom, while the unmelted parts are carried up on the sides to be exposed above the melted portion. When the charge is melted, it is poured by revolving the furnace, as is shown by Fig. 3, the blast and fuel being shut off meanwhile.

The details of the construction may be varied to suit the different requirements.

The flues after leaving the flange 43 may be curved downward or in any desired direction instead of passing upward, as shown. The methods of supporting and revolving the furnace-body may be varied from those shown so long as the two movements are provided for.

What I claim is—

1. A furnace provided with a single opening and mounted to be revolved in two planes, combined with a set of fixed, concentric flues for supplying air and fuel and discharging furnace-gases, respectively, and means for connecting the furnace and flues and otherwise closing the former, and means for rotating the furnace while so connected.

2. The combination with a furnace having an opening on one side, of means for introducing heating material through said opening and discharging it on all sides of the same in directions approximately parallel to the wall surrounding the opening, and a discharge-conduit located centrally in said opening.

3. A furnace with a single opening mounted to revolve and to tilt back and forth, a set of flues for conducting the blast and taking away the furnace-gases, said furnace and flues movable in relation to each other in addition to the revolving and tilting movement above mentioned.

4. The combination with a furnace having a revolving and vertically-tilting body with an opening in its upper side, of a flue provided with a flange adapted to fit over and completely close said opening about the flue, means for holding the flue and the furnace together with the opening thus closed, a second flue, within the first, communicating with the interior of the furnace, and means for revolving the furnace while the parts are thus held.

5. The combination with a furnace having an approximately pear-shaped body open at

its upper end, of a set of flues one within the other opening into the furnace through said upper end, means for adjustably inclining the furnace, means for closely but revolubly connecting the open end of the furnace with the ends of the flues, and means for rotating the furnace.

6. The combination with a normally inclined furnace having an opening above only, 10 of a set of flues, one within the other, in position for communicating with the interior of the furnace through said opening, means for detachably connecting the flues with the furnace and excluding the surrounding air, means 15 for at will moving the furnace bodily from the flues, and means for at will tilting the furnace vertically.

7. The combination with a normally inclined furnace having an opening above, only, 20 of a set of fixed flues in position for communicating with the interior of the furnace through said opening, means for detachably connecting the flues with the furnace and closing the latter, means for at will moving the furnace 25 bodily from the flues, and means for at will tilting the furnace vertically.

8. The combination with a normally inclined, revoluble furnace having an opening in its upper end, of a set of fixed flues in position 30 to communicate with the interior through said opening, means for moving the furnace bodily to and from the flues without changing its inclination, means for revolubly connect-

ing the furnace with the flues, and means for tilting the furnace vertically to empty it. 35

9. The combination with a suitable horizontal base, of a furnace arranged to slide upon the base and provided with an opening at one side of the medial plane, and a closure fixed in position to close the opening when the furnace is moved toward it upon the base. 40

10. The combination with a suitable base, of a furnace sliding upon the base and having an opening at one side of the medial plane, a closure in position to close said opening when 45 the furnace slides toward it on the base, and means for locking the furnace against sliding movement.

11. The combination with a furnace having a single opening, of a blast-tube discharging 50 inwardly through the opening, a discharge-flue located in the blast-tube, a fuel-pipe passing toward the furnace in the discharge-flue and thence outward into the blast-flue to discharge with the latter. 55

12. A furnace with an opening in the side, a flue for the escape of the gases of combustion located in the center of the opening, an air-blast flue and fuel-jets located around the margin of the opening. 60

Signed at Chicago this 12th day of May, 1903.
